UNITED STATES PATENT OFFICE

2,459,044

CONSTRUCTION FORM FOR CONCRETE FLOORS

Joseph J. Pirz, Flushing, N. Y.

Application March 13, 1947, Serial No. 734,340

3 Claims. (Cl. 25—131.5)

1

This invention relates to the construction of concrete floors. More particularly, the invention resides in the provision of readily assembled and demountable pouring forms for repeated use on successive jobs or successive parts of the same job.

An important object of the invention is to provide concrete forms by which concrete structures may be efficiently and rapidly produced, with consequent economy. A further object of the invention is to provide for the rapid assembly and disassembly of the forms, and to enable them to be repeatedly used with minimum "wear and tear" and replacement of parts.

In the construction of concrete floors, my invention contemplates the attachment and support of the forms to the steel beams and girders of the conventional building framework. Thus the steel floor beams have hung upon them the beam-form units to receive the concrete by which the beams are enclosed, and these units support the floor forms which extend from beam to beam for receiving the concrete which is to form the floor. The various parts of the beam-enclosing form units are so constructed that they are secured in place on the beam by assembly members applied and disconnected from below, without having to disturb the set concrete when it is time to remove them, as will become clear from the subsequent description.

In the accompanying drawing—

Figure 1 illustrates in perspective, with parts in section, a floor construction as it is built up on the floor beams or girders of the typical steel structure.

Figure 2 is a side elevation, with parts in section, illustrating the application of an implement for locking together the bottom channel and a side wall of a floor form.

Figure 3 is a similar view showing the implement at the completion of its locking operation.

Figure 4 is a detail section through a part of the implement and the parts being secured together, as viewed on the line 4—4 of Figure 3.

Figure 5 is a detail sectional elevation through another portion of the parts being secured together, illustrating the use of an intermediate locking member of different construction from that shown in Figures 3 and 4.

Figure 6 is a horizontal section of the details shown in Figure 5, as viewed on the line 6—6 thereof.

Figure 7 is a top plan view, with parts broken away, illustrating one embodiment of a two-part floor section form extending from beam to beam

for receiving the concrete which is to form the floor.

Figure 8 is a side elevation thereof.

Figure 9 is a detail sectional elevation thereof on the line 9—9 of Figure 7, showing the securing together of the adjacent portions of two of the floor forms.

Figure 10 is an underneath view of the parts shown in Figure 9.

Figure 11 is a perspective view of a unitary all-metal floor or wall form.

Figure 12 is a cross section thereof on the line 12—12 of Figure 11.

Figures 13 and 14 are similar cross sections of wall or floor forms embodying alternative types of walls formed by folding the edges of the sheet metal web.

Figure 15 is a cross-sectional elevation through the lower portion of a modified construction of beam form to extend the concrete fill beneath the steel beam or girder.

Figure 16 is a detail sectional view on a line 16—16 of Figure 15, illustrating in cross section the metal spacers employed for registering the form with the steel beam, and

Figure 17 is a perspective view, with parts broken away, illustrating the construction and assembly of wall forms to produce a concrete wall simulating on its outer face a clapboard wall.

As previously indicated, the forms comprise in general the beam forms, immediately associated with the steel beams or girders, and the floor forms which extend across the space between the beam forms. Referring to Figures 1 and 3;

20 indicates the steel I-beams of any standard or conventional type extending between columns or other supports for carrying the floor load. The web 21 of an inverted rolled metal channel having the side flanges 22 and 23 is placed against the

bottom of the I-beam 20 where it is centered by suitable members, such as for example the lugs 24, 25 struck out from the web 21 so as to confine the base of the I-beam 20 between them. Rolled metal side walls 26, 27 are placed against the

channel flanges 22, 23. These side walls are provided with shelf brackets 28, 29, suitably secured to the respective side walls by welding or other conventional means, to provide supports for the floor forms, as will later be seen. The web

portion 21 of the inverted channel is perforated at 30, 31, at intervals along its length to receive suspension wires 32 which are hung over the top of the I-beam and extend through the perforations 30, 31 into the space beneath the web, adjacent the inner surfaces of the flanges 22, 23.

These flanges 22, 23 are recessed at 33, 34 in registry with similar recesses 35, 36 in the adjacent side walls 26, 27. By deflecting the depending ends of the suspension wires 32 outwardly through the registered recesses 33, 35 and 34, 36, as shown for example in the right-hand side of Figure 3, the inverted channel and the adjacent side walls, which constitute the beam form, are secured together and to the I-beam 20 by which they are supported. Any suitable tool or implement may be employed to deflect a loop of each end of the suspension wire 32 outwardly through the registering recesses mentioned. I have illustrated in Figures 2 and 3 an implement suitable for this purpose which is described and claimed in my copending application, Serial No. 706,640, filed October 30, 1946. This implement comprises a main body portion 37 on which are mounted the operating parts of the flange and wall-engaging and the wire-bending members. Extending rigidly from this main body 37 is a hand lever or arm 38 which is grooved or recessed at 39 to receive a toggle link 40 and at 41 to receive a jaw member 42. One end of the link 40 is pivoted to the arm 38 at 43, and the jaw member 42 is pivoted to the arm at 44. The jaw member 42 is of T-section at its gripping face 45, and is slotted at 46 to receive the cross pin 47 of its actuating lever 48, which lever is bifurcated or forked at the end to embrace the jaw member. An adjustable screw 49 threaded in the boss or enlargement 50 extends into the slot 46 to provide an adjustable limit stop. The toggle link 40 is connected with the actuating lever 48 by means of a fulcrum pin 51, the link being disposed in a groove or recess 52 formed in the lever 48. The lever system described constitutes a toggle for actuating and locking the jaw member 42 upon the outer face of the side wall 27 against the pressure of the opposing main body portion 37 of the implement, which engages the opposite face of the channel flange 23, as can be seen in Figures 2, 3 and 4. The adjustment screw 49 can be turned to compensate for any irregularities, or to take up wear, so that the toggle can be swung through the dead center into and out of locking position. To ensure the application of the implement in proper relation with respect to the recesses 34 and 36, the main body 37 may be fitted with a registering pin 53 which enters registering perforations 54, 55 of the flange 23 and side wall 27 respectively.

The body portion 37 of the implement has a groove 56 extending across its gripping face to receive and guide the suspension wire 32. This groove 56 terminates in a wall 57 which serves as a stop or abutment for the projecting end of the suspension wire 32. Beneath this groove 56, the body portion 37 is chambered at 58 to receive a plunger 59 carrying a bending die 60 whose outer end is concave to embrace the suspension wire 32 immediately adjacent the registered recesses 34 and 36 of the channel flange 23 and the side wall 27. Actuation of the bending plunger 59 toward these recesses 34 and 36 from the normal position shown in Figure 2 to the position shown in Figure 3 deflects a loop of the suspension wire 32 through the recesses 34, 36 where it can be secured by a wedge pin 61, as shown in the lower part of Figure 1. To actuate the plunger 59, I prefer to employ a rack and pinion connection such as illustrated in Figure 4. Thus the plunger 59 is formed with the rack 62 engaged by the teeth of a pinion 63 fixed on a pinion shaft 64 (Figures 2, 3 and 4). This pinion shaft

64 projects from the body portion 37, and its projecting end is fitted with an operating lever 65. A journal plate 66 surrounding the shaft 64 may be secured by screws 67 to the face of the body portion 37. This plate has an inner collar 68 (Figures 2 and 3) which abuts against the pinion 63 to hold the latter in its proper position.

The plunger 59 has a perforated lug 69 (Figures 2 and 3) projecting rigidly from one side thereof to receive a rod 70. This rod has a roughened wire-gripping end 71 projectable into the groove 56 through an aperture of the main body portion 37. It also has a fixed collar 72 behind which is disposed a coil spring 73 confined between the collar 72 and the perforated lug 69. A stop collar 74 may be secured on the rear end of the rod 70 to engage the lug 69 for retracting the rod when the wire-bending plunger is retracted, so as to keep the rod out of the path of the suspension wire 32 when the implement is being placed in position on the flange 23 of the channel and the side wall 27. It will be apparent that the rod 70 will be resiliently urged forward as the plunger 59 is actuated to deflect the wire, thus causing the rod 70 to grip the wire and hold it securely against displacement of its intermediate portion while its projecting end is being bent into the loop form shown in Figure 3. The performance of this operation at 20 the two ends of each suspension wire 32 simultaneously locks the channel and the two side walls to each other and to the supporting I-beam which they enclose. Wedge pins 61 (see Figure 1) are inserted in the loops outside the side walls of the form, after the plunger 59 has been withdrawn. The implement may then be removed and applied to the next position where a suspension wire 32 is to be installed. Three of these suspension wires 32 are seen on each of the supporting I-beams shown in Figure 1 of the drawing. The frequency of their occurrence will, of course, depend upon their strength and the magnitude of the load which they must support. For this reason, the perforations 30, 31 of the channel web, the recesses 33, 34 in the channel flanges and the recesses 35, 36 in the side walls are provided in proper registration with each other at regular intervals where it may be necessary to apply suspension wires 32.

50 Figures 5 and 6 show an additional locking device for securing the channel flanges to the side walls, if desired. This device comprises a T-shaped clip 75 which may be struck out of sheet metal of suitable gauge so as to pass through recesses 76 and 77 of the channel flanges 22, 23 and the side walls 26, 27 which are disposed at intervals between the suspension wire recesses already described. These T-shaped clips are perforated at 78 to receive wedge pins 79. In Figure 1, I have shown by way of example provision for two of these supplementary locking devices between each two suspension wires. The recesses in the channel flanges and side walls for receiving the suspension wires and the T-shaped clips can be, and preferably are, alike, so that either suspension wires or clips may be employed where the recesses occur. The perforations 30, 31 in the channel webs should also 65 occur where the recesses in the channel flanges and side walls are provided.

The apparatus thus far described in detail pertains mainly to the assembly of the beam forms and their securing on the supporting I-beam. 70 The side walls 26, 27 and the inverted channel

comprising the web 21 and flanges 22, 23 constitute the beam form into which concrete is to be poured around the I-beam 20.

In Figure 15, a slight modification of the construction above described is illustrated. In this modification, provision is made for spacing the inverted channel at a prescribed distance below the I-beam. Thus, the beam form comprises side walls 80, 81 and the inverted channel having the web 82 with dependent flanges 83, 84. The web 82 of the inverted channel is in this embodiment recessed at intervals to receive the tongues 85 of spacer plates 86 which are notched at 87 to receive the base flange of the I-beam 88. The tongues 85 of the spacer plates 86 may be welded, riveted or otherwise secured in the web 82 of the channel. Here again the parts constituting the beam trough or form are secured to each other and suspended from the supporting I-beam by a suspension wire indicated at 89, substantially as already described.

The side walls of the beam form, whether constructed as shown in Figure 3 or as shown in Figure 15, are provided with shelf brackets, such as illustrated at 28 and 29 in Figure 3, for receiving and supporting the floor forms. These floor forms may vary in construction, but in general they comprise web or panel portions and stiffening frames or walls. In some cases the web or panel portions may be separate and removable, especially where they are of, for example, plywood mounted in metal stiffening frames. In other cases, the web or panel portion and the stiffening frames may be of unitary, all-metal construction. Figures 7, 8, 9 and 10 illustrate an embodiment in which the floor forms have separate plywood panels 90 removably seated in protective, sheet metal stiffening frames having side and end walls 91 and panel-supporting flanges 92. The frame is formed by first folding the sheet metal stock upon itself, to provide double side wall thickness, and then at right angles to provide the sunken, panel-supporting flanges, as clearly seen in Figure 9. The flanges 92 are cut away at intervals to permit the folding of the stock into a rectangular frame with the panel flanges 92 meeting at the corners on a miter, as indicated at 93. The walls 91 are recessed at 94 to admit T-shaped clips 95 perforated at 96 to receive the wedges 97, for locking together the walls of two adjacent floor forms, as shown in Figures 9 and 10. Perforations 98 (see Figure 8) alternate with the recesses 94 to receive the registering pin 53 of the previously-described bending implement shown in Figures 2, 3 and 4, where the frames are to be locked together by the looping of a tie wire as described in connection with the use of the suspension wire 32.

The use of the floor forms of the type shown in Figures 7, 8, 9 and 10 is illustrated in the construction shown in Figure 1. Here it will be seen that the floor forms are laid on the shelf plates 28, 29 of adjacent beam forms, after which the concrete 99 is poured over the floor forms and into the troughs of the beam forms and levelled off to form the true floor surface.

In place of the particular construction of floor forms shown in Figures 1, 7, 8, 9 and 10, I may employ other types of floor forms, for example any of the all-metal floor forms illustrated in Figures 11, 12, 13 and 14. In Figures 11 and 12, for example, the form comprises the metal panel 100 which is welded onto the longitudinal stiffening walls 101, 102 and 103 and to the end walls

104, 105. The end walls 104, 105 may be simple rolled plates, whereas the longitudinal walls 101, 102 and 103 are folded metal with flanges 106, 107, 108 and 109. The flanges 106, 109 are turned inward, whereas the flanges 107, 108 are turned outward. The flange arrangement on the side walls 101, 103 is important to enable the side walls of adjacent forms to contact each other when laid on the supporting shelves 28, 29 (Figures 1 and 3) so that they may be secured together by the T-shaped clips 95 or other securing means. For this purpose, the side walls are provided with the recesses 110, 111 and the perforations 112, 113 similar to those already described. The longitudinal stiffening wall 102 may likewise be provided with similar recesses 114 and perforations 115, and the end walls 104, 105 may be provided with corresponding recesses 116, 117 and perforations 118, 119 to be available for use where special connections are to be made.

Figures 13 and 14 illustrate two further modifications of the floor form, these embodiments having integral panel and side walls of folded sheet metal construction. In Figure 13, the sheet metal stock is folded to provide the panel 120 with side walls 121, 122, whereas in Figure 14 the sheet metal stock is folded to provide the panel 123 and side walls 124, 125. In each case, the panel may be reenforced by a folded sheet metal flange 126 or 127, welded to the under surface of the respective panel. The metal is folded inward to form the side walls 121, 122 in Figure 13, whereas it is folded outward to form the side walls 124, 125 in Figure 14. End walls, similar to those shown in Figure 11, may be employed in the constructions shown in Figures 13 and 14, if desired. All the walls and flanges may be understood to have the recesses and perforations for interconnection by means of the T-shaped clips or other securing means such as heretofore described.

Regardless of the particular construction of floor forms employed, it will be apparent from the example shown in Figure 1 that they are intended to bridge the spaces between successive I-beams by being laid upon the shelf brackets 28, 29 to receive and support the concrete fill, as already described. It will be understood that after the concrete has been poured upon the floor forms and into the beam forms and properly levelled over the exposed floor surface, it is permitted to set for the proper length of time to become self-sustaining. Thereafter, the various securing pins or wedges are removed, the T-shaped clips driven out and the suspension wires 32 severed where exposed, so as to permit the disconnection and removal of the various form members. It will be noted that all these operations are readily performed from below the concrete without the necessity of disturbing or marring the exposed floor surface. The parts of the forms may then be applied to the production of succeeding floor units.

Any of the floor forms shown and described can be applied to the construction of vertical walls and columns. In such applications, the panel would, of course, be directed toward the concrete fill, and the stiffening walls and flanges would be directed outward. In the case of extended walls, a number of the forms may be placed adjacent to each other and locked together by the T-shaped metal clips and wedge pins or equivalent members.

A special adaptation of the panelled forms to

the construction of concrete walls is illustrated in Figure 17. In this embodiment, tie rods 128 pass through perforations 129 in the panels or webs 130 and 131 adjacent stiffening flanges 132 and 133 which are recessed at 134 and 135 and perforated at 136, substantially as already described in connection with the recesses and perforations in the stiffening flange 102 shown in Figure 11. The perforations 136 are intended to receive the registering pin 53 of the wire-bending implement, previously described, which operates upon the tie rod 128 to deflect a loop through the recess in the stiffening flange, which loop is then locked by the insertion of a wedge pin 137. All the stiffening walls and flanges of the form units illustrated in Figure 17 are preferably equipped with similar recesses and registering perforations to fit them for the reception of locking clips 95, tie rods 128 or other securing means. Figure 17 illustrates the use of tie rods for locking the two opposing form walls in proper relation to each other to maintain the correct pouring space between them. This particular feature is embodied in my previous patent application above mentioned. Figure 17 also shows a type of wall form which may be employed to simulate a stepped or clapboard effect in the outer wall. This effect is obtained by rolling the sheet metal stock into channel form in which the web portion 131 adjoins a folded upper flange 138 of greater width and a rolled lower flange 139 of less width. The effect is plainly discernible in the drawing. Between these upper and lower flanges 138 and 139, the stiffening flanges 133 are connected by welding or riveting to the web 131. These stiffening webs 133 are of folded metal similar to the stiffening flanges 102, 126 and 127 previously described, but are tapered from top to bottom to correspond with the widths of the upper and lower flanges 138, 139.

I claim:

1. A concrete form and support comprising in combination a supporting beam, an inverted channel disposed in substantially parallel relation beneath said supporting beam, side walls disposed against the outer faces of the channel flanges and extending upward above the channel web to provide therewith a trough to receive the concrete, and a suspension wire hung over the

supporting beam and passing downward through the channel web and outward through the channel flanges and the adjacent side walls to suspend the assembled members from the top of the supporting beam.

2. A concrete form and support comprising in combination a supporting beam, an inverted channel disposed in substantially parallel relation beneath said supporting beam, side walls disposed against the outer faces of the channel flanges and extending upward above the channel web to provide therewith a trough to receive the concrete, a suspension wire hung over the supporting beam and passing downward through the channel web and looped outward through recesses in the channel flanges and the adjacent side wall, and pins in the loop portions of said suspension wire outside said side walls to lock the members in assembled relation.

3. A concrete form and support comprising in combination a supporting beam, an inverted channel disposed in substantially parallel relation beneath said supporting beam, side walls disposed against the outer faces of the channel flanges and extending upward above the channel web to provide therewith a trough to receive the concrete, said channel web, channel flanges and side walls provided with registering apertures, and a suspension wire hung over the supporting beam and passing by way of said apertures downward through the channel web and outward through the channel flanges and the adjacent side walls to suspend the assembled members from the top of the supporting beam.

JOSEPH J. PIRZ.
